UNITED STATES PATENT OFFICE

140,658

DESIGN FOR A TUMBLER

Alfred J. F. Erbe, Weston, W. Va.

Application January 3, 1945, Serial No. 117,231

Term of patent 7 years

(Cl. D36—8)

To all whom it may concern:

Be it known that I, Alfred J. F. Erbe, a citizen of the United States, residing at Weston, in the county of Lewis and State of West Virginia, have invented a new, original, and ornamental Design for a Tumbler, of which the following is a specification, reference being had to the accompanying drawing, forming part thereof.

I claim:

The ornamental design for a tumbler, as shown.

ALFRED J. F. ERBE.
